[57] CLAIM

The ornamental design for a container for storing brushes or the like, as shown and described.

DESCRIPTION

FIG. 1 is a perspective view of a container for storing brushes or the like, showing my new design;

FIG. 2 is a top plan view thereof;

FIG. 3 is a bottom view of my new container;

FIG. 4 is a perspective view of the device, shown with the top and bottom halves separated; and

FIG. 5 is a side elevational view of the device as shown in FIG. 1, shown on a larger scale and partially in section.
